Inventor:

Vinton E. Sisson.

UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

POSITIONING DEVICE FOR RAILWAY-CAR COUPLERS.

Application filed April 19, 1926. Serial No. 102,978.

This device relates to means for automatically positioning the coupler of a railway car by gravity.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range".

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car

moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the number of broken knuckles and guard arms on couplers which members are frequently bent or broken when the couplers are not within coupling range. Such devices also reduce the number of accidents to trainmen as they are not required to go between the cars and position the coupler preparatory to coupling.

It has been found advantageous to have the coupler support cast integral with the striking casting to obtain a four sided member which reinforces the end sill, draft sill and associated parts and my device is especially adaptable to such a combined casting.

A great majority of the movement of a railway car is upon a straight track or a curved track having a large radius and at least half of the friction between a coupler and whatever supports it is caused by its fore and aft movement in service therefore, a coupler causes more friction (and consequent wear) between it and its support when it is in its central normal position than when in any other position.

An object of the invention is to decrease the friction and consequent wear between the coupler and the positioning device by supporting the coupler solely upon means independent of the positioning device when the coupler is in central normal position and to so arrange the positioning device that when the coupler moves laterally its weight is entirely shifted from the said means to the positioning device and conversely when the coupler moves back to its normal central position its weight is shifted back to said means.

Such an arrangement makes it possible to provide any desired bearing area between the coupler and its (ultimate) support when the coupler is in its normal position which

is not possible, or at least practical, in a swing motion device, such as shown in Figs. 1, 2 and 3 having a journaled support or in a roller type of device, such as shown in Figs. 4, 5 and 6 having a line bearing.

In the drawings:

Fig. 1 shows a typical application of the device to a railway car with the coupler in normal position.

Fig. 2 is the same as Fig. 1 with the coupler moved to extreme lateral position.

Fig. 3 is a section on line 3-3 of Fig. 1.

The striking casting or buffer block 2 is attached to the draft sill 3 or other part of the car body in any suitable manner and the coupler support 4 is attached thereto or preferably cast integral therewith. The coupler 5 rests upon the carriage 6 which engages the support 4 in such a manner as to restrict its movement longitudinally of the car but permits its movement sidewise of the car. This is preferably accomplished by providing a U-shaped support having spaced apart walls 7-8 between which the carriage moves sidewise of the car but is restricted in its movement longitudinally of the car. The carriage is also provided with means 10 to restrict the lateral movement of the coupler relative thereto.

The carriage 6 is suspended from a part of a car body by swingable links 20. This carriage is positioned so that when the coupler is in normal central position it rests upon the support 4, as shown in Fig. 1.

When the coupler moves laterally the carriage rises and the weight of the coupler is shifted from the support 4 to the carriage 6, as shown in Fig. 2.

I claim:

1. In a railway car; the combination of a coupler support, a laterally movable coupler resting upon the support when in normal position, a carriage swingably supported by links to a part of said car so as to swing loosely under the coupler when the coupler is in normal position, said carriage and links arranged to lift the coupler upon lateral movement thereof and to cause the coupler to return to normal position by gravitation. 40

2. In a railway car; the combination of a coupler support, a laterally movable coupler resting upon the support when in normal position, a carriage swingably supported by links to a part of said car so as to swing loosely under the coupler when the coupler is in normal position, said carriage and links arranged to lift the coupler upon a predetermined amount of lateral movement thereof and to cause the coupler to return to normal position by gravitation. 50

3. In a railway car; a coupler resting solely upon a rigid support when in normal central position and resting solely upon a swingable centering device when moved to either side of said central position. 60

4. In a railway car, the combination of a coupler support, a coupler carriage swingably supported by links to a part of the car, the coupler bearing surface of the carriage being normally below the coupler bearing surface of the coupler support; said parts so arranged that upon a predetermined amount of swinging movement of the carriage the coupler bearing surface of the carriage is elevated above the coupler bearing surface of the support. 70
